UNITED STATES PATENT OFFICE.

GEORGE M. NELLANS, OF WICHITA, KANSAS.

TENDER FOR TRACTION-ENGINES.

SPECIFICATION forming part of Letters Patent No. 739,703, dated September 22, 1903.

Application filed March 30, 1903. Serial No. 150,209. (No model.)

To all whom it may concern:

Be it known that I, GEORGE M. NELLANS, a citizen of the United States, residing at Wichita, in the county of Sedgwick and State of Kansas, have invented certain new and useful Improvements in Two-Wheeled Water-Tenders; and I do declare the following to be a full, clear, and exact description of the invention, such as will enable others skilled in the art to which it appertains to make and use the same.

This invention is an improved two-wheeled water-tender adapted to be attached to a traction-engine between the latter and the grain-
15 separator or other machine drawn or operated by the traction-engine and which is designed to keep in line with the engine when it is moving backward or forward; and it consists in the peculiar construction and combination of
20 devices hereinafter described and claimed.

In the accompanying drawings, Figure 1 is a top plan view of the frame of a water-tender embodying this invention, showing the same connected to a traction-engine, the latter being indicated diagrammatically. Fig. 2 is a vertical transverse sectional view of the frame of the water-tender, taken on the plane indicated by the line *a a* of Fig. 1. Fig. 3 is a vertical longitudinal sectional view of the
25 same, taken on the plane indicated by the line *b b* of Fig. 1. Figs. 4 and 5 are detail elevations of the cap-pieces and the pivotally-mounted wheel-supporting elements.

In the embodiment of the present invention
35 cap-pieces 1 are provided, which are connected together by cross-bars 2. The latter are disposed one above the other. Intermediate the cap-pieces are wheel-supporting elements 3, which are independently mounted for horizontal angular movement between the said cap-pieces. Each of the said wheel-supporting elements is here shown as a block 4, having an outwardly-extending spindle 5 for a supporting-wheel 6 and an inwardly-extending arm 7, forming a lever by which the block
45 may be turned between the cap-pieces. In the present embodiment of the invention the block 4 and cap-pieces are provided with co-engaging cylindrical recesses and shoulders, as at 8, at their opposing sides, in which are circular ball-races and bearing-balls 10, the same forming antifriction-bearings between

the blocks 4 and the cap-pieces. In the present embodiment of the invention the respective cap-pieces and blocks 4 are connected together by centrally and vertically disposed pivot-bolts 11. The arms 7 of the wheel-supporting elements are here shown as connected to the blocks 4 by screw-couplings 12, said blocks having threaded openings and said arms having screw-threaded outer ends engaging said threaded openings and being further provided with jam-nuts 13, which bear against the inner sides of the blocks.

A longitudinally-disposed draw-bar 14 passes between the upper and lower cross-bars 2, and the end portions thereof are connected to caps 1 by side brace-bars 15, as shown. These brace-bars are in practice preferably made of angle iron or steel, and their intermediate portions are connected together by curved brace-bars 16, the latter being also connected to the upper and lower cross-bars 2, as shown. The inner ends of the arms 7 of the wheel-supporting elements operate between the intermediate braces 16, the latter being concentric with the pivotal axis of the wheel-supporting elements.

The draw-bar 14 is provided near its ends with direction elements, which are here shown as sheaves 17. The latter are connected together by a flexible connecting element 18, here shown as a cord, but which may be in practice a chain, cable, strap, or the like, and the said flexible connecting element has its respective leads attached to the inner ends of the arms 7, so that the wheel-supporting elements are caused to turn in unison and their respective spindles 5 to be always maintained in parallel relation to keep the tender in line with the traction-engine to which it is coupled, both when the engine is moving in a straight course and when the same is describing a curve.

In Fig. 1 the traction-engine is indicated at 95 A diagrammatically, and its pivotal axle B is shown as connected by operating-cords or the like elements to the inner ends of the arms 7. Hence the wheel-supporting elements of the tender-frame are turned automatically by a pivoted axle or truck of the traction-engine. It will be understood that one end of the draw-bar is coupled by any suitable means to the traction-engine. When the latter is em-

ployed for operating a grain - separator or other machine, said grain-separator or machine will be also coupled to the opposite end of said draw-bar 14.

5 From the foregoing description, taken in connection with the accompanying drawings, the construction and operation of the invention will be readily understood without requiring a more extended explanation.

10 Various changes in the form, proportion, and the minor details of construction may be resorted to without departing from the principle or sacrificing any of the advantages of this invention.

15 Having thus described the invention, what is claimed is—

In a vehicle of the class described, a frame having a longitudinally-disposed draw-bar, cross-bars, above and below it and having cap-
20 pieces at their ends, braces 15 connecting the

ends of the cross-bars and the draw-bar, braces 16 connecting the intermediate portions of the said braces and cross-bars, direction elements carried by the draw-bar, wheel-supporting elements pivotally mounted between the cap-pieces at the sides of the frame for angular movement, and provided with inwardly-extending arms which operate between the braces 16, and a flexible element connecting the direction elements and having its respective leads connected to the said arms to maintain the supporting-wheels in parallel relation, substantially as described.

25 In testimony whereof I have hereunto set my hand in presence of two subscribing wit-
nesses.

30 GÉORGE M. NELLANS.
